UNITED STATES PATENT OFFICE.

CHARLES J. HEAGUEY, OF NEW BRUNSWICK, NEW JERSEY.

RAIL-JOINT.

992,558.

Specification of Letters Patent.

Patented May 16, 1911.

Application filed December 16, 1910. Serial No. 597,657.

To all whom it may concern:

Be it known that I, CHARLES J. HEAGUEY, a citizen of the United States, residing at New Brunswick, Middlesex county, New Jersey, have invented new and useful Improvements in Rail-Joints, of which the following is a specification.

This invention relates to rail joints, the object being to provide a simple and effective method of joining and alining the abutting ends of two sections of rails.

One of the essential features of the invention is a splice-plate located at the outer side and connected to the webs and ties of the rails, the plate having a flanged top in a plane with the tread of the rails, combined with a brace of suitable construction to engage the lower portion of the flanged top. The brace is formed integral with a base-plate on which rests the rail, and it has a side wing extending at right angles to the brace whereby the brace is fastened to the web of the rail. This base-plate also has holes to enable the plate to be fastened to the ties of a railroad. The flanged top of the splice-plate is tapered at both ends so that the wheels of a car will not strike the ends of the flange, thus avoiding battering of the ends of the flanged top and consequent loosening of bolts and displacement of parts.

The novel features of the invention are more fully set forth in the following specification and illustrated in the accompanying drawing in which;

Figure 1 is a side elevation of a rail-joint embodying this invention. Fig. 2 is a plan view of the same. Fig. 3, is a vertical section taken along the line $x-x$ Fig. 1. Fig. 4 is a vertical section taken along the line $y-y$ Fig. 1. Fig. 5 is a perspective view of a brace-plate.

In this drawing the letter a designates a pair of rail sections having abutting ends, and b is a splice-plate whereby the two sections are secured together. The splice-plate has a continuous flanged top c the inner portion of which is in contact with the under side of the top of the rails and it has a flanged base d . A fish-plate e is arranged along the inner sides of the rails. The fish-plate and the splice-plate are fastened to the rail sections by a series of bolts f which extend through the webs of the rails and thus secure the two sections of rails to-

gether. The splice-plate base d forms a foot which is adapted to rest on a plate g which extends under the base of a rail section and forms a support for the splice-plate and rail. The plate g is provided with an integral brace h extending upwardly from the plate and adapted to engage the under portion of the flange c . The inner portion of this brace is shaped to fit the outer side portion of the splice-plate and it is slotted as shown in Fig. 5 to rest on to and embrace the flange d of the said plate. The brace-plate h also has a side wing i extending at right angles to the brace and of suitable construction to be fastened to the web of the rail by one of the said series of bolts f .

The plate g has holes j and the splice-plate flange d is provided with slots j' for the insertion of a spike to fasten the splice-plate and also the brace-plate to the ties of a railroad, not shown.

The upper portion of the flange c is tapered or shveled at each of its ends so that the wheels of a car will roll up the incline and thus avoid end thrust and subsequent displacement of the splice-plate.

The base-plate has a clip k punched in the plate and this clip is adapted to engage the flanged foot of the splice-plate, to give proper alinement and keep the brace at right angles to the rail.

It will be seen that when the splice-plate with the brace-plate is fastened to the rails, and the ties, it gives practically a continuous rigid joint to the rail sections, keeping the same in proper line and preventing wear of the tread of the rail.

One of the advantages of the invention is that all the wear at the abutting ends of the rail sections is taken up by the splice-plate and in other places along the rails is uniformly distributed.

I claim:

1. In a rail joint, the combination with the abutting ends of a pair of rail sections, of a splice-plate having an upper flange the top of which is in a plane with the tread of the rails, and provided with a lower flange, a brace-plate including a base-plate having a brace formed integral with the plate to engage the under portion of the top flange and to fit the face and embrace the lower flange of the splice plate, said base plate being adapted to support the

splice-plate and the rail, and devices for fastening the splice plate and the brace plate to the tie and web of the rails.

2. In a rail joint, the combination with
5 the abutting ends of a pair of rail sections,
of a splice-plate having an upper and lower
flange, a brace-plate including a base-plate
having a brace formed integral with the
plate to engage the under portion of the
10 top flange and to fit the face and embrace
the lower flange of the splice-plate, a side
wing formed integral with the brace, and
devices for fastening the said wing and the
splice-plate to the tie and web of the rail.
15 3. In a rail joint, the combination with
the abutting ends of a pair of rail sections,
of a splice-plate having an upper and lower

flange, said upper flange being tapered at
the top end, a brace-plate comprising a
base-plate having a brace formed integral 20
with the plate to engage the under portion
of the top flange and to fit the face and em-
brace the lower flange of the splice-plate,
said base plate being adapted to support
the splice-plate and the rail, and devices 25
for fastening the splice-plate and the brace-
plate to the tie and web of the rail.

In testimony whereof I have hereunto set
my hand in the presence of two subscribing
witnesses.

CHARLES J. HEAGUEY.
